(57) CLAIM

The ornamental design for an artificial snow flake with lights, as shown and described.

DESCRIPTION

FIG. 1 is a front, top perspective view of an artificial snow flake with lights, showing my new design;

FIG. 2 is a rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof; and,

FIG. 9 is an enlarged view of a portion labeled, 'FIG. 9' in FIG. 7.

The even dashed broken lines in the figures illustrate portions of the article that form no part of the claimed design. The dash dot dash lines in FIGS. 7 and 9 are for the purpose of depicting the boundary line of the enlarged view and form no part of the claim.

1 Claim, 9 Drawing Sheets(56)
